Primary Examiner — Marianne Pandozzi(74) *Attorney, Agent, or Firm* — Steven E. Shapiro(57) **CLAIM**

The ornamental design for a shaker mug, as shown and described.

DESCRIPTION

FIG. 1 is a top perspective view of a shaker mug;
 FIG. 2 is a front view of the shaker mug;
 FIG. 3 is a rear view of the shaker mug;
 FIG. 4 is a left side view of the shaker mug;
 FIG. 5 is a right side view of the shaker mug;
 FIG. 6 is a top view of the shaker mug;
 FIG. 7 is a bottom view of the shaker mug; and,
 FIG. 8 is a bottom perspective view of the shaker mug.
 The broken lines shown in the drawings represent portions of the shaker mug that form no part of the claimed design.
